PORTABLE LABORATORY UTILITY CART

John P. Salsgiver, West Acton, Mass., assignor to United Technical Corporation, Auburndale, Mass., a corporation of Massachusetts

Filed Aug. 15, 1967, Ser. No. 8,272

Term of patent 14 years

(Cl. D16—2)

FIG. 1 is a perspective view of a portable laboratory utility cart, showing my new design; and

FIG. 2 is an end view of the movable support taken from the right hand end of FIG. 1.

I claim:

The ornamental design for a portable laboratory utility cart, as shown.
